[57] ABSTRACT

This invention relates to a detonator oriented towards the prevention of failure due to "arcing" or premature firing caused by ambient RF energy. (i.e., Radio, radar or microwave transmitters and static electricity.)

3 Claims, 1 Drawing Figure

PATENTED SEP 4 1973

3,756,154

Edward H. Snyder
INVENTOR

SAFETY DETONATOR

The FIGURE illustrates a detonator of the conventional electric blasting cap type. The electric detonator has lead-in wires 1 connected to a firing initiator 2 which detonates a charge 3.

This detonator, however, contains two new features. These are: a fluoride-carbon insulation 1 lined to prevent "arcing;" and the firing initiator 2 is a thermistor which upon receipt of a predetermined current through wires 1 heats to ignite. This non-inductive device prevents the ambient RF energy device from forming a tuned circuit at random radio frequencies.

Thus having described the invention, the claims are

as follows:

1. In an electric blasting cap, leadin wires (1) a firing initiator connected across the leadin wires (2) and an explosive charge (3) adjacent to the firing initiator 5 adapted to be ignited by said firing initiator, wherein said initiator is a thermistor.
2. Within an electric blasting cap as set forth in claim 1 where there is further provided an insulating means disposed around the firing initiator.
- 10 3. In an electric blasting cap as set forth in claim 2 where the insulating means is a fluoride-carbon insulation.
